HIGH FREQUENCY AMPLIFIER SYSTEM

Frederick A. Kolster, New York, N. Y., assignor to
 Federal Telegraph Company, San Francisco,
 Calif., a corporation of California

Application February 2, 1925, Serial No. 6,259
 Renewed June 1, 1932

4 Claims. (Cl. 179—171)

This invention relates to a system for amplifying high frequency electrical energy, and especially to a radio frequency system employing electronic emission amplifier tubes.

Such radio frequency systems are in quite general use in connection with broadcast receivers, in which there may be one or more stages of radio frequency amplification. It has been found that in such systems, the efficiency varies with the frequency. Since the present broadcast range of from 200 to 550 meters corresponds to a variation in frequency between 546 kilocycles and 1500 kilocycles, it is seen that even for this broadcast range, material variation in the efficiency of the amplifier can be expected unless some means be employed to render the operation more uniform. It is one of the objects of my invention to make it possible to operate the amplifier at substantially the same efficiency independently of this frequency variation.

It is another object of my invention so to arrange matters in such a system that no adjustment is necessary to secure this beneficial effect, after the broadcast receiver is once placed into operation.

It is still another object of my invention to provide a system of amplification in which the currents flowing in the output circuits of the successive stages may be controlled automatically to cause substantially similar amplifying effects independently of frequency variations.

My invention possesses other advantageous features, some of which with the foregoing, will be set forth at length in the following description, where I shall outline in full that form of the invention which I have selected for illustration in the drawing accompanying and forming part of the present specification. Although I have shown in the drawing but one embodiment of my invention, I do not desire to be limited thereto, since the invention as defined in the claims may be embodied in other forms also.

Referring to the drawing:

Figure 1 is a wiring diagram of a broadcast receiver and amplifier embodying my invention; and

Fig. 2 shows curves for explaining the operation of the system disclosed in Fig. 1.

In Fig. 1 the system is shown as applied to an amplifier system of two stages, each stage having

a three-electrode electron emission tube 11 or 12; but of course the invention may be embodied in a system having less or a greater number of stages. The first tube 11 has an output circuit consisting of the control electrode 13 and an electron emitting electrode 14, connected to a circuit 15 which is arranged to carry the electrical currents or impulses to be amplified. In the case of a broadcast receiver, circuit 15 is usually a circuit tuned to the frequency of reception as by the condenser 16, and coupled to any appropriate source of signal energy. The electron emitting electrode 14 is in this instance in the form of a filament heated by current supplied from a battery or other source 17.

The output circuit in which the amplified impulses or currents flow, is connected between the plate or anode 18 and the filament 14, the space between these two electrodes being bridged by the flow of electrons from filament 14. Since the operation of such amplifiers is now well-known, it is sufficient at this point to state that the output circuit of such devices must include a source of direct current voltage, such as a battery 19, to impress a positive potential on plate 25 or anode 18 as regards the filament 14.

In most radio frequency amplifiers as heretofore constructed, the circuits are inductively coupled together so that the amount of current passed by the coupling arrangement will increase with an increase in frequency, as the impedance of an inductance is a function of the frequency of the current, and no attempt has been made to compensate for the fact that this current is a function of the frequency of operation, whereby greater transfer of energy is obtained for high frequencies than at low frequencies. I overcome this disadvantage by so arranging the output circuit that the value of that portion of the current affecting the succeeding stage or the detector, no longer varies materially for different frequencies within a given range, even if the total output current varies. To accomplish this result, I use two impedance branches or paths for the output current, and the current flowing in one of these branches is controllable as desired, by the proper choice of constants. This branch comprises a condenser C_1 and an inductance L_1 in series, while the other branch consists of an inductance L_2 . It can be shown that by proper

choice of values of L_1 , C_1 and L_2 , the division of current in the two branches can be made to vary with the frequency. To understand how this is accomplished, attention is now directed to Fig. 2.

5 In this figure, the abscissae represent frequencies, and the ordinates represent reactances. The range of frequencies that is of interest in connection with broadcast receivers is represented by the horizontal distance between the two 10 vertical lines 20 and 21, corresponding respectively to 546 kilocycles, and to 1500 kilocycles. A calculation according to well-known formulae, of the reactance of branch $C_1 L_1$ will produce a 15 curve of the form shown at either 22 or 23 depending upon the relative absolute values of capacitance and inductance. These curves are plotted from the formula

$$X_1 = 2\pi f L_1 - \frac{1}{2\pi f C_1}$$

20 It is evident that when the frequency f approaches zero, the value of reactance X_1 increases negatively without limit. This is shown in Fig. 2 by making curves 22 and 23 asymptotic as regards the vertical line 24 passing through the origin. On the other hand, for large values of f , the reactance X_1 is positive. By proper choice 25 of the values of C_1 and L_1 , it is possible to vary the slope of the curve, and to make it have 30 positive ordinates at or near the 546 kilocycle line 20. The curve 23 is similar to curve 22 except for a different ratio of C_1 and L_1 , the curve 23 being steeper. Preferably the constants are such that the reactance reduces to zero (corresponding to a tuned condition) at a frequency just a little below the lower limit of operation, or 35 below 546 kilocycles.

The total reactance impedance X of the output circuit, or of the two branches in parallel will be

$$40 X = \frac{1}{\frac{1}{X_1} + \frac{1}{X_2}}$$

Therefore it is evident that as the system is 45 tuned to different frequencies, the total reactance will increase with increased frequencies.

The inductance L_2 forming the second branch is preferably chosen so as to make its reactance about equal to that of the other path at or near the higher limit of frequency. This is shown by 50 the curves 25 and 26, corresponding respectively with the curves 22 and 23. These curves are in fact straight lines passing through the origin, for they obey the law that

$$55 X_2 = 2\pi f L_2$$

which is the equation of a straight line.

Of course only this latter path L_2 is available 60 to permit the flow of direct current in the output circuit. But the radio frequency amplified current has two paths, and divides between them. At the high frequency limit, the radio frequency current is preferably about evenly divided between the paths, because the impedances of both 65 paths are about equal. As the frequency of operation is reduced, the current is no longer evenly divided, but instead a larger share of it passes through path $L_1 C_1$. By careful choice of the constants $L_1 C_1$ and L_2 , this automatic compensation 70 can be made fairly accurate.

The succeeding stage, if there be one, is coupled 75 to the coil L_1 preferably by the aid of a secondary coil L_3 , whereby the current in coil L_1 is the only factor affecting this succeeding stage. The scheme of connection for this stage need not be

described in detail, for it is substantially similar to that already described. The input circuit of tube 12 is connected across the tuning condenser 27 which is in a closed circuit with coil L_3 whereby the input circuit may be selectively tuned to any 5 frequency within a given range of radio frequencies; and its output circuit also includes the two branch circuits L_4 , and C_5-L_5 . The proportions of the elements L_4 , C_5 , and L_5 are determined as before.

Still further stages may be employed as desired, similarly constructed. However, since the principle would be exactly the same as before, I show only the two stages, and indicate a receiver 15 28 as coupled by the aid of coil L_6 to the coil L_5 . The coupling between coils L_4 and L_5 and between coils L_5 and L_6 is somewhat critical, but when once the proper value is found, the amplifier system operates properly and without requiring other attention.

The manner of operation of the system is evident from the foregoing description. The condensers 16, 27, and 29 are adjusted to selectively tune the stages to the frequency of operation. Due to the choice of constants as explained, the 25 efficiency of the amplifier system remains substantially unaltered without making coupling adjustments no matter what the frequency of operation may be.

I claim:

1. In an amplifier system for amplifying electrical impulses of radio frequency the frequency of which may vary between limits, an electronic emission tube, and an output circuit for said tube comprising a pair of parallel paths, one consisting substantially entirely of inductance, and the other of an inductance and a capacity in series, said two paths being so arranged that at the high frequency limit of operation the reactances of both paths are substantially equal, and at the low frequency limit, both have positive reactances but of differing values, and a selectively tuned circuit coupled to the inductance in said second parallel path whereby the current flow in the path having this lower reactance is utilized as the amplified electrical impulse to the exclusion of the current in the other path.

2. In a system of the class described comprising two circuits, the second taking energy from the first, said first circuit having two paths one of which is coupled to said second circuit, means for tuning said second circuit selectively through a given range of radio frequencies, the two separate paths of said first circuit comprising impedance elements so proportioned that the ratio of the current through the said coupled path to the current in the uncoupled path decreases with increase in the selected frequency, whereby the energy transfer ratio between said circuits will tend to remain constant.

3. In a system of the class described an amplifier having control and output circuits, a pair of separate paths in said output circuit, one of said paths comprising an inductance element and the other path an inductance and a condenser element in series, means for tuning said control circuit through a selected range of frequencies, means for inductively coupling said control circuit with at least one path of said output circuit, whereby energy is transferred to said control circuit, said elements being so proportioned with respect to each other that the ratio of the current through said first named path to the current through said second named path increases with an increase in frequency, whereby the en-

ergy transfer between said output and control circuits will be independent of frequency.

4. The method of reactively coupling the output circuit of a high frequency amplifier with another circuit comprising automatically varying the current flowing in an interlinking reactive element so that for relatively high radio frequen-

cies the current will be relatively small but for lower radio frequencies simultaneously introduced into the output circuit the current will be relatively high, whereby substantially a constant energy transfer ratio will be maintained throughout a given frequency range. 5
